UNITED STATES PATENT OFFICE.

JOHN S. BIRCH, OF ORANGE, NEW JERSEY.

HOLDING-TOOL.

SPECIFICATION forming part of Letters Patent No. 228,860, dated June 15, 1880.

Application filed December 29, 1879.

To all whom it may concern:

Be it known that I, JOHN S. BIRCH, of Orange, in the county of Essex and State of New Jersey, have invented a new and useful Improvement in Holding-Tools, of which the following is a specification.

Figure 1 is a perspective view of the improvement. Fig. 2 is a perspective view of the outer case. Fig. 3 is a side elevation, partly in section, of the inner case. Fig. 4 is a sectional elevation of the improvement. Fig. 5 is a side elevation, partly in section, of the outer case, shown as containing the improvement.

The invention consists in constructing the holding-tool with the case in the shape of a tube flattened upon two or four sides to give a side support to the jaws; also, in forming grooves in the sides of the jaws and in the inner surface of the sides of the end of the case to prevent the jaws from slipping when under strain; and, also, in the combination, with the case, of a bent lever, so that more power can be applied to the wrench, as will be hereinafter fully described.

Similar letters of reference indicate corresponding parts.

A represents a case which is open at one or both ends, and is made in the form of a tube flattened upon two or four sides. In the forward end of the case A are placed two jaws, B, in the inner side of the outer parts of which are formed longitudinal angular grooves, to cause them to take a firmer hold upon the object to be held. The outer ends of the jaws B are slightly inclined toward each other when drawn into the case, but will gradually become parallel as they are projected more and more. The outer sides of the jaws B are so formed as to fit into the narrow side parts of the end of the cavity of the case A. The middle and inner parts of the jaws B are slightly curved inward and outward, as shown in Fig. 4, so that their inner sides, B', may rock longitudinally upon each other as the said jaws are projected from and drawn into the case A. This construction, by changing the point of contact as the jaws are projected farther and farther, gives the effect of short jaws when the jaws are but slightly projected and of longer jaws as they are pro-

jected farther and farther, so that the jaws at the point of contact will always be at a sharp angle with each other. The outer sides of the inner ends of the jaws B are notched to receive the ends of the U-spring C, which ends are bent inward to enter the said notches.

With this construction the spring C presses the inner ends of the jaws B toward each other, so that their outer ends will spread as the jaws are projected from the case A. The inner end or bend of the spring C enters the end of the tube D, where it is secured to the said tube D by a pin, E, passing through the said tube D and through the bend of the said spring C, or by other suitable means.

The tube D is made of the same shape as the case A, of such a size as to fit into and slide back and forth in the said case A, and has its outer end closed to prevent dust from entering the case A. The tube D is pressed outward, drawing the jaws B inward, by a spiral spring, F, the outer end of which rests against the closed end of the tube D, and its inner end rests against a shoulder, flange, or other stop, G, formed upon or attached to the case A.

With this construction the jaws B are pressed outward or projected by pressing the tube D inward, and the said jaws are drawn inward when the pressure upon the tube D is removed by the elasticity of the spring F. This action of the spring F causes the jaws B to grasp and hold the object to which they are applied and renders a constant effort to keep the implement applied to the object unnecessary.

The lower end of the case A may be strengthened by a pin, H, passed through the end part of the case A, between the jaws B, as shown in Figs. 1, 3, 4, and 5.

With this construction, when power is applied to the wrench to turn the object grasped by the jaws B the sides of the jaws B will bear against the sides of the end of the case A, and will thus be much more firmly supported than when the case is made cylindrical and the strain has to be wholly supported by the pin H. This construction of the case A also enables the case A to be made much lighter than would otherwise be practicable.

I is an outer case, closed at one end, and

made of the same shape as the case A, and of such a size that it may be slipped over the case A, as shown in Fig. 5, to prevent dust from entering the implement when being carried. In the case I, near its closed end, is formed an oblong hole, J, of such a shape and size as to receive the case A, so that the case I may be used as a lever for turning the wrench.

10 K is a lever, which is provided with a handle, L, at one end. The other end of the lever K is bent over at right angles, so that the said bent end may be passed through the square hole M in one side of the case A and through the round hole N in the other side of the said case. The bent part of the lever K is made longer than the distance through the case A, and its forward part is made round, and its inner part is made square, so as to fit into the square hole M, to prevent the lever from turning while being used.

With this construction the lever K may be withdrawn a little to raise its square part out of the square hole M, so that it may be turned around parallel with the case A, for convenience in carrying it. The lever K may have a nut or washer attached to its end to permanently connect it with the case A. Upon the sides of the jaws B are formed grooves O, to engage with corresponding grooves P in the inner surface of the side parts of the end of

the case A, as shown in Figs. 1, 3, and 4. The grooves O P prevent the jaws B from slipping when the wrench is under strain, as they would be liable to do if the points in contact 35 were smooth. The grooves O P may be made transversely or longitudinally with the jaws B and case A, as may be desired, the transverse grooves preventing the jaws B from slipping longitudinally and the longitudinal grooves 40 preventing the jaws B from slipping laterally.

Having thus fully described my invention, I claim as new and desire to secure by Letters Patent—

1. In a holding-tool, the oblong case A, combined with correspondingly-shaped jaws B, to support the strain on said jaws, as described. 45

2. The side-grooved jaws B, combined with a case correspondingly grooved in the inner surface, to prevent said jaws from slipping, as 50 set forth.

3. The combination, with a case having a square hole on one side and a round one on the other, of the lever K, having a bend to give more power, and a square as well as a round portion, the said lever being adapted to be partially withdrawn, as and for the purpose specified. 55

JOHN S. BIRCH.
